UNITED STATES PATENT OFFICE

168,786

BROILER

Morris A. Feinstein, Chicago, Ill.

Application February 26, 1952, Serial No. 18,675

Term of patent 3½ years

(Cl. D81—10)

To all whom it may concern:

Be it known that I, Morris A. Feinstein, a citizen of the United States, residing at Chicago, in the county of Cook and State of Illinois, have invented a new, original, and ornamental Design for a Broiler, of which the following is a specification, reference being had to the accompanying drawings, forming part thereof.

Fig. 1 is a perspective view of a broiler in the closed position, showing my new design; and

Fig. 2 is a perspective view of the same in the open position.

The back of the design is plain, and the left-hand side is identical with the right-hand side.

I claim:

The ornamental design for a broiler, as shown and described.

MORRIS A. FEINSTEIN.
